UNITED STATES PATENT OFFICE.

THEODORE L. VALERIUS AND OLAF LARSEN, OF FORT ATKINSON, WISCONSIN, ASSIGNEES TO THE CREAMERY PACKAGE MFG. COMPANY, OF CHICAGO, ILLINOIS, A CORPORATION OF ILLINOIS.

CUTTING MACHINE.

Application filed November 15, 1919. Serial No. 338,283.

To all whom it may concern:

Be it known that we, THEODORE L. VALERIUS and OLAF LARSEN, residing at Fort Atkinson, in the county of Jefferson and State of Wisconsin, have invented certain new and useful Improvements in Cutting Machines, of which the following is a specification.

Our invention relates to machinery for use in cutting plastic material into pieces of a given size and also embodies devices for facilitating the wrapping of the cut pieces. The embodiment of our invention disclosed is particularly adapted for cutting ice cream into bricks and delivering the bricks in spaced relation on a moving carrier, each one neatly laid on a piece of paper of the proper size for wrapping it.

One of the objects of our invention is to provide a machine that will quickly and accurately sever pieces of ice cream of the proper size.

Another object is to provide an arrangement whereby the resulting bricks may be quickly and neatly wrapped without being touched by the hand of the operator.

Further objects and advantages of our invention will become apparent as the description proceeds.

The device we have illustrated, and in which the principles of our invention have been embodied, comprises cutting machinery adapted to sever and deliver the bricks, receiving machinery adapted to present a sheet of paper in proper position to receive each brick as it is delivered from the cutting machinery, driving means for the cutting and receiving machinery, and means for producing properly synchronized action of said driving means. In the device illustrated, the synchronizing is accomplished by employing a unitary driving means for both the cutting and receiving machinery so designed that properly synchronized action is inherent in the mode of operation of the machine.

Referring to the accompanying drawings, Figure 1 is a plan view of a device according to our invention. Fig. 2 is a sectional view on the line 2—2 of Fig. 4. Fig. 3 is an end view looking from the left in Figs. 1 and 2 with the paper roll removed. Fig. 4 is a section on the line 4—4 of Fig. 2. Fig. 5 is a plan view of the wrapping table and

shows a second conveyor belt which may be used if desired.

The various elements of our improved device may be properly mounted or assembled with respect to a main frame 10 having suitable supporting feet 11. A flat table 12 on top of the frame 10 is adapted to receive a large block of the material to be cut. Any small amount of liquid material accumulating on the table during the use of the machine may drain or be removed with a squeegee into a suitable trough 13 adapted to receive the same. Upwardly directed lips 12a along the periphery of the table except where the trough and cutting knife are located, prevent dripping.

The cutting mechanism provided comprises in this instance a knife 14 carried by the main cross head 15 which is supported on two vertical rods 16 and 17 each slidably mounted in bearings at 18 and 19 in the frame 10. A lower cross head 20 connects the lower ends of the vertical rods 16 and 17 and is adapted to be reciprocated vertically by the driving mechanism to be described later. A vertical plate or guide 21 extends longitudinally of the table 12 as illustrated in Fig. 1, and is supported by its attachment to a backing piece 22 having projecting rods 23 passing through studs 24 stationary on the rear edge of the upper portion of the frame. Set screws 25 (see Fig. 3) are adapted to clamp the rods 23 in adjusted position.

A pusher plate 26 is suitably attached, as by a bearing portion 27 and set screw 28 to the end of a longitudinally slidible pusher rod 29. The pusher rod 29 has a series of notches 30 and passes through a reciprocating forwarding device having a dog 31 adapted upon rearward motion of the forwarding device to slide over the notches, but upon forward motion thereof to engage them and force the pusher rod and plate forward towards the cutting knife 14. After a large block of cream or other material has been placed on the table 12 the alternate actuation of the pusher rod 29 and the cutting knife 14 will alternately move the mass of material on the table forward under the knife and sever the forwardly projecting portion of the material to form a brick of suitable size.

An additional knife 32 extending longitudinally in

front of the center of the main cutting knife 14 may be used to cut the portion lying in front of the main knife into two equal parts, as for instance, when the device 5 is designed or adjusted to cut quart bricks with knife 14 and it is desired to cut each quart brick in half.

The receiving mechanism we have provided comprises a conveyor belt 33, a paper 10 roll 34, and means for feeding the paper forward to the belt and periodically severing the portion already on the belt. The belt and paper feeding means are intermittently operated, each operation occurring 15 simultaneously with the actuation of the pusher rod 29.

The mechanical transmission for automatically performing the above-mentioned operations will now be described. The main 20 drive sleeve 35 is continually rotated during the operation of the machine by any suitable or preferred source of power, such, for instance, as an electric motor 36 suitably mounted in an out of the way place 25 on a bracket 37 on the side of the frame 10. A sprocket chain 38 engaging suitable sprockets drives the shaft 39 at a reduced speed from the motor 36, which last-mentioned shaft through suitable reduction 30 gearing drives a sleeve 40 on a second intermediate shaft 41. A suitable toothed clutch 42 is adapted to engage the sleeve 40 to drive the intermediate shaft 41 on which it is splined. Lastly, a pinion on 35 the intermediate shaft 41 meshing with a gear 44 on the main drive sleeve 35 transmits motion to said sleeve.

The sleeve 35 carries a single cam 45 adapted to actuate alternately each of two 40 rollers 46 and 47, one located above and the other below the axis of rotation of the cam. While separate cams for the rollers might obviously be provided we prefer the construction shown. The lower roller 45 is suitably supported on a shaft 48 extending through centrally upstanding lugs on the lower cross head 20 and also through one of these lugs laterally to a lug 51 near the end of the cross head. A lever 52 suitably pivoted on a transverse shaft 53 has a bifurcated end straddling the shaft 48 and at its other end is adapted to actuate a vertical plunger 54 through a short connecting link 55^a pivotally connected to the 55 plunger 54 and the lever 52. The plunger 54 reciprocates vertically in suitable guide bearings carried by the frame 10. A stationary knife blade 55 is located below the center of the table 12 above the path of the 60 paper from the paper roller 34. A movable cutting blade 56 suitably pivoted at 57 receives motion from the vertical plunger 54 through a short connecting link 58 pivoted to the plunger and cutting knife.

65 As the cam 45 rotates in a clockwise direc-

tion from the position shown in Fig. 2 the lower roller 47 will be forced down, moving the lower cross head, guide rods, upper cross head and cutting knife 14 down to bring the knife against the table 12. The 70 movable cutting blade 56 will also be actuated through the vertical plunger 54 and lever 52 to sever the paper extending from the roll onto the conveyor belt. We have provided means for holding the 75 roller 47 against the cam 45 and returning it to its uppermost position after the projecting portion of the cam has passed by, in the shape of a suitable counterweight 59 mounted on the end of a pivoted lever 60. The roller 61 on the opposite end of the lever 60 bears against a suitable surface provided on the lower crosshead 20 in all positions of the lever and crosshead.

After the main cutting knife 14 and paper 85 cutting knife 56 have been actuated as above described and returned to their initial positions, the cam 45 in its further rotation will actuate the upper roller 46 moving a bell crank lever 62, resiliently urged toward 90 the position illustrated in Fig. 2, by a suitable tension spring 63 connected into the center of a tension member 64 extending from the upwardly directed arm of the bell crank lever to a suitable attachment 95 on the frame 10. The motion of the bell crank lever 62 actuates suitable mechanism for feeding the pusher rod 29, the paper from the paper roll 34, and the conveyor belt 33. The connections for this purpose 100 include a guide rod 65 sliding in suitable guide bearings 66 and 67 and carrying a head 68 connected through a pivoted link 69 with the upper end of the upper arm of the bell crank lever 62. A turn-buckle 70 105 may be provided as part of this link for adjusting the stroke of the head 68. At its rear end the guide rod carries an inwardly projecting forwarding plate 71 extending across under the pusher rod 29 and carrying the dog 31 pivotally mounted between suitable upstanding lugs or ears 72.

The conveyor belt 33 is carried by rollers 73 and 74, the outer roller 74 being mounted on a longitudinally slidable bearing, sliding in the slot 75^a at the end of the projecting arms 75 and adjustably tensioned by means of suitable springs 76. A short endless chain 77 passing over a sprocket wheel 78 on the shaft of the inner roller 73 and an idler sprocket 79 slidably mounted by means of the slotted connection indicated at 80 to properly tension the chain, has a plurality of equally spaced special links formed in its upwardly projecting dogs 81. Upon each actuation of the crosshead 68, a ratchet 82 mounted thereon is adapted to engage the next in succession of the dogs 81 to rotate the roller 73 and actuate the conveyor belt.

A paper feed roller 83 of the same size as the rollers for the receiving belt is driven from the inner roller 73 at the same speed by a suitable sprocket chain 84. A smaller 5 rubber faced roller 85 geared to the paper feed roller so as to have the same surface speed and bearing against the surface of the feed roller cooperates with the feed roller to grip and force the paper from the paper roll 10 34 through suitable guides 86 past the cutting edge of the stationary knife 56 and forward onto the conveyor belt. The stroke of the dog 31 and the ratchet 82 is designed to be appreciably greater than the distance between 15 the successive notches 30 or dogs 81 respectively, with which they engage, so that upon each actuation of the bell crank lever 62 these parts will move up behind the next in succession of the parts they actuate 20 and force them forward to a certain point.

The frame 10 is U-shaped in end view and reinforced by stretcher rods 103 which rods also act as pintles for the lower edges of doors 104, equipped with suitable latches 25 105 and knobs 106. Except for slots 107 to allow reciprocation of the lower cross head 20, these doors and the walls of the frame 10 constitute a complete enclosure for the moving parts under the table 12.

30 Suitable safety means are provided to prevent actuation of the pusher rod 29 far enough to move the pusher plate 26 under the cutting knife. We have provided a hand control lever 87 mounted on a control shaft 88 journaled in suitable bearings 89. A crank arm 90 on the end of the shaft 88, through a pivotally connected link 91, actuates the lever 92 to rotate the clutch shaft 93 to engage the clutch 42 with the sleeve 40 and start the operation of the machine. In doing this, the link 91 is swung into alignment with the crank arm 90 and the long arm of the lever 92 rises, tensioning the spring 94. It will be apparent that as soon as the hand lever 87 is moved enough to throw the crank 90 and link 91 out of alignment, the spring will immediately throw out the clutch. An upwardly projecting arm 95 carried by the shaft 88 and in this instance formed integral with the hand lever 87 is connected to a transversely slideable plunger 96 by a suitable link 97. The plunger 96 as clearly indicated in Fig. 1 carries a roller 98 at its outer end. A safety dog 99 mounted 45 for longitudinal adjustment on the pusher rod 29 and suitably clamped in position by set screws 100 is adapted to engage a roller on the end of a slightly bent lever 101 carried by the forwarding plate 71. This lever is downwardly offset as indicated in Fig. 2, and its short arm underlies the forwarding plate 71 and is adapted to engage the roller on the plunger 96. A light tension spring 102 is adapted to hold the lever 101 in the 55 position indicated in Fig. 1.

Actuation of the hand lever 87 to start the machine will move the plunger from the position illustrated in Fig. 1 into rather close proximity to the short arm of the lever 101. The step-by-step operation of the pusher 70 rod 29 will eventually bring the safety dog 99 where the return stroke of the forwarding plate will force the end of the lever against the dog, rotating the lever so that its short arm will engage the roller 98, displacing the hand lever slightly whereupon the spring 94 will act and release the clutch. 75

It is desirable that the rod 29 should be released at the end of each forward stroke of the plate 71 so that it may be slid back to its initial position. This facilitates handling masses of cream of various sizes. We have provided a stationary bar 108 extending parallel to the rod 29 and having an upwardly projecting cam portion 109. A small pin 80 110 projects laterally from the dog 31 and in its rearmost position rides up on the cam 109, lifting the dog 31 clear of the teeth 30.

The operation of the device is as follows: In cutting quarts the knife 32 is not used 90 and a detachable plate 111 (see Fig. 5) forms the front edge of the table 12. The synchronous operation of the belt 33 and pusher plate 26 will operate to carry away the last brick, if any, and to project the end 95 of the mass of cream, as indicated in dotted lines at 112, past the edge of the table. The plunger arm and belt then come to rest and the knife 14 severs the projecting mass of cream which falls onto the piece of paper 100 carried partly out from under the edge of the table by the last motion of the belt 33. Simultaneously with the cutting of the cream another length of paper on the belt 33 under the table is severed by the knife 56. 105

A wrapping table 113, underlying the belt 33 and projecting laterally on each side thereof, as illustrated in Fig. 5, is preferably provided. An operator or operators may stand on one or both sides of the belt 33 110 and by grasping the edges of the pieces of paper on which the bricks are laid, draw them to one side onto the lateral projections of the table where they may be conveniently wrapped in the paper. We may also provide a suitable continuously moving belt 114 adapted to receive objects falling off the end of belt 33 to convey them in any desired direction. When the belt 114 is used, the wrapped bricks are laid back on 115 the belt 33 and deposited by it on the belt 114 which may convey them to any desired point for packing, storing or shipping purposes. When the belt 114 is not used, the wrapped bricks are of course deposited in 120 suitable receptacles by the operators working at the table 113. 125

In cutting pints the plate 111 is replaced by the plate 115 (see Fig. 1) and the knife 32 is mounted on the crosshead 15. The pint 130

pieces indicated in dotted lines at 116 in Fig. 1, upon being severed, will fall somewhat diagonally away from each other onto the belt 33. In cutting pints as above outlined, two rolls of paper 34 are preferably mounted on the machine each half as wide as the paper used for wrapping quarts, and the laterally directed pint bricks will fall side by side, each on a separate piece of paper.

10 While we have illustrated and described in detail the particular embodiment of our invention at present preferred it should be clearly understood that the description is only for the purpose of illustration and 15 many variations and modifications will naturally occur to those skilled in the art. It will, for instance, be obvious that increasing the distance by which the table projects past the vertical plane of the cutting knife 14, 20 may cause the severed brick to fall off the table during actuation of the pusher plate 26 and belt 33 instead of during actuation of the knife to sever the brick as illustrated. We aim in the subjoined claims to cover all 25 such legitimate modifications and variations.

We claim as our invention:—

1. In an ice cream severing machine, a table, means for intermittently pushing a mass of material across said table to project 30 beyond said table, means for intermittently severing the projecting portion of said mass of material and allowing it to fall off said table, a conveyor belt adapted to receive the severed portions, means for intermittently feeding said conveyor belt and for intermittently feeding paper on to said conveyor belt, means for intermittently severing the last portion of paper fed on to said belt, means for simultaneously actuating said 35 paper and material severing means, and means for simultaneously actuating said pushing means, conveyor belt and paper feed means.

2. In a device of the class described, a 45 table, a pusher plate and a cutting knife, means for moving said pusher plate toward said cutting knife, a source of power, means for connecting said source of power to said means for moving said pusher plate, a manual control element, operative connections 50 including a toggle mechanism between said connecting means and said control element, a spring normally tending to actuate said connecting means to disconnect said source 55 of power, said toggle mechanism being adapted to prevent such disconnection, and automatic means associated with said pusher plate adapted to break said toggle.

3. In an ice cream severing machine, a 60 table, a cutting knife, pushing means, means in the nature of a single movable cam adapted to produce synchronized alternate actuation of said knife and the said pushing means, and automatic means for arresting

the motion of said cam before said pushing means is moved into the path of said knife. 65

4. In an ice cream severing machine, a table, a cutting knife, a pushing means and a receiving means, and means in the nature of a single movable cam adapted to produce 70 synchronized alternate actuation of said knife and of said pushing and receiving means.

5. In an ice cream severing machine, a 75 table, a cutting knife, a pushing means, a receiving means, and a paper feeding means, and means in the nature of a single movable cam adapted to produce synchronized alternate actuation of said knife and of said pushing, receiving and feeding means. 80

6. In an ice cream severing machine, a table, a cutting knife, a pushing means, a receiving means, a paper feeding means and a paper cutting means, and means in the nature of a single movable cam adapted to produce synchronized alternate actuation of said cutting knife and said paper cutting means, and of said pushing, receiving and paper feeding means. 85

7. In a device of the class described, a 90 table, a frame, a cutting knife located on said frame above said table, means for reciprocating said frame vertically to actuate said cutting knife, and a paper-cutting mechanism beneath said table operatively connected with said frame for simultaneous actuation therewith. 95

8. In a device of the class described, a 100 table, a pusher plate adapted to push an article off said table, a conveyor belt adapted to receive an article pushed off said table, means for feeding paper onto said conveyor belt to receive said article, and a single reciprocating element operatively connected to said pusher plate, receiving belt and paper feeding means for simultaneous intermittent operation thereof. 105

9. In an ice cream severing machine, a 110 table, means for moving a series of spaced separate pieces of paper out from under the edge of said table, and means for severing portions of ice cream and allowing them to fall from the edge of said table onto said pieces of paper, a work table for wrapping said portions beside said conveyor, and another conveyor at the end of said first conveyor, adapted to receive wrapped portions from the first conveyor. 115

10. In a device of the class described, a 120 table, a pusher plate and a cutting knife, means for actuating said pusher plate, a source of power, a manual control element, mechanism operated by said manual control element for connecting said source of power to said actuating means, said mechanism having a trigger action and automatic means associated with said pusher plate for producing an initial movement of said control 125

element when said pusher plate has been moved to a predetermined point whereby said trigger action mechanism becomes effective to disconnect said source of power 5 from said actuating means.

11. In an ice cream severing machine, a table, conveyor means for moving a series of spaced separate pieces of paper out from under the edge of said table, means for 10 severing portions of ice cream and allowing them to fall from the edge of said table onto said pieces of paper, and a plurality of work tables level with said conveyor on opposite sides thereof.

15 12. In a device of the class described, vertically reciprocable operating elements, horizontally movable operating elements, contact means for alternately operating said vertically reciprocable and said horizontally 20 movable elements, and gravity means associated with said vertically reciprocable elements and resilient means associated with said horizontally movable elements, for maintaining said contact means in operative 25 engagement.

13. In a device of the class described, a table, a vertically reciprocable frame, pushing means associated with said table adapted to push material along said table, cutting means adapted to sever a portion of material to allow it to drop off said table, a conveyor belt adapted to receive said severed portion, means for alternately and intermittently operating said cutting means 30 and said pushing means and conveyor belt, means operatively associated with said conveyor belt for simultaneous actuation therewith for covering said belt with paper, and means operatively associated with said 35 frame and actuated simultaneously therewith for severing the paper on said conveyor belt into separate pieces.

40 14. In a device of the class described, a table, a cutting knife, a pushing means, a

receiving means, a paper feeding means, 45 and a paper severing means, a source of power, a transmission adapted to alternately and intermittently actuate said cutting knife and paper severing means, and said pushing means, receiving means and paper- 50 feeding means, manually controlled elements adapted to connect said source of power to said transmission and automatic safety means adapted to disconnect said source of power from said transmission when said 55 pushing means has been moved to a predetermined point.

15. In an ice cream severing machine, a table, a frame supporting said table and constituting a housing, a vertically recip- 60 roitable knife above said table, a pushing means operating above said table across the face thereof, a conveyor belt extending out from under said table, paper feeding means under said table adapted to feed paper to 65 said conveyor belt, paper severing means, and a transmission for alternate actuation of said cutting knife and said paper severing means, and of said pushing means, convey- 70 or belt and paper feeding means, said transmission and said paper severing means being housed in said frame.

16. In a device of the class described, a table, centrally located pushing means acting across the face of said table, a conveyor 75 belt extending out from under one edge of said table and a connection for simultaneous operation of said pushing means and said conveyor belt comprising a longitudinally 80 slidable rod extending along one side of said table operatively connected to said pushing means and to a transmission for said conveyor belt.

In testimony whereof we have hereunto set our hands.

THEODORE L. VALERIUS.
OLAF LARSEN.
